UNITED STATES PATENT OFFICE.

MICHAEL H. FLAHERTY, OF PHILADELPHIA, PENNSYLVANIA.

LOCK-SEALED ENVELOPE.

1,422,045.

Specification of Letters Patent.

Patented July 4, 1922.

Application filed May 26, 1920. Serial No. 384,389.

To all whom it may concern:

Be it known that MICHAEL H. FLAHERTY, a citizen of the United States, residing at Philadelphia, in the county of Philadelphia and State of Pennsylvania, have invented 5 certain new and useful Improvements in Lock-Sealed Envelopes; and I do hereby declare the following to be a full, clear, and exact description of the invention, such as 10 will enable others skilled in the art to which it appertains to make and use the same.

This invention relates to a lock sealed envelope, and the object is to provide certain novel means whereby the inspection of the 15 contents of an envelope by an unauthorized person may be prevented.

A further object is to provide, in one form 20 of device, an element which shall be provided with tongues extending therefrom, to be secured by adhesive material to the usual flap of the envelope, and to other portions of the envelope including the rear wall thereof.

A still further object is to provide, in 25 another form of the device, an envelope the closing flap of which shall be formed with a tongue adapted to be passed through a slot in the rear wall of the envelope and to be secured by adhesive material to the inner 30 side of the rear wall and to the end flaps of the envelopes, this tongue and the adjacent portion of the flap first named receiving, if desired, the embossed stamp usually employed on stamped envelopes issued 35 by the Post Office Department.

A still further object is to provide for 40 the sealing of the tongue or tongues extending from the closing flap of the envelope or from a separate stamp, on both sides of said tongue or tongues.

With the foregoing and other objects in view, the invention consists in the novel construction or formation of the various elements and in the manner of assembling the 45 elements, as will be more fully described and claimed.

In the drawings:

Figure 1 is a view of the envelope sealed by the use of the securing device first 50 scribed, and ready for mailing.

Figure 2 is a view showing the stamp or securing device partly inserted.

Figure 3 shows this envelope with the closing flap in the position assumed before

folding down and sealing, a portion of the 55 rear wall of the envelope being broken away, for showing the overlapping end flaps.

Figure 4 is a plan view of the blank from which this envelope is made.

Figure 5 is a view of another form in 60 which three sealing tongues are employed, the central tongue being ready to enter the slot provided therefor, and the other tongues being free.

Figure 6 illustrates a form employing a 65 separate stamp having four tongues adapted to cooperate with four slots in the envelope.

Figure 7 shows this form of stamp, or sealing device, detached.

Figure 8 shows a further modification in 70 which the single sealing tongue is connected directly with the closing flap.

Figure 9 shows the use of three sealing tongues connected with the closing flap.

Figure 10 shows the stamp of the first 75 form, detached.

In carrying out my invention I employ an envelope which may be sealed with or without a stamp, and in any event the usual closing flap is sealed as the first step in the operation. The address is preferably written on the side on which the envelope is sealed and stamped, in order that it may be apparent at once if any attempt is made to interfere with the sealing devices. The end 80 flaps 10 and 12 preferably overlap, the blank for the envelope being therefore of approximately the form shown in Figure 4, in which the front wall or section is designated 14, the rear wall or section is designated 15, and the 85 flap 17. The outer edge of rear wall 15 is turned over as indicated at 16. This element 15 is provided with slots 18 and 19, and a slot 20 is formed in flap 17. 90

The stamp is of the form shown in Figure 10, and includes a central portion 21 on which the stamp per se is printed or embossed, the element also including tongues 22 and 23 for cooperation with the aforesaid 100 flap.

In Figure 1 I have shown an envelope of this form also provided with perforations at 24 and 25, and it is obvious that these perforations may be used in any form of the device. 105

The stamp is provided with a coating of adhesive material on both sides, and is fur-

ther provided with slots 22' and 23' and with apertures 26 and 27 at the ends of the respective tongues.

The envelope is first sealed in the usual manner—that is by closing the flap 17 and sealing it. The special stamp provided for the purpose is then applied. By using the narrow blade of a small penknife the lower tongue 23 is passed through slot 19, by 10 causing the point of the blade to engage the end of the tongue at the apertured portion thereof; it being understood that the device may be used without the aperture previously punched, if desired. The blade of the knife 15 is then moistened and passed through slot 22' for sealing the under side of tongue 23. The blade being withdrawn, the upper side of the tongue 23 may be sealed in a similar manner. The upper tongue 22 is secured in 20 a like manner, and the triple sealing operation is completed.

In the form shown in Figure 5 the usual sealing or closing flap 30 is provided with a tongue 31 having a slot 32 therein, that portion of the tongue above referred to being adapted to carry a stamp, if desired. A stamp may however be employed independently. The end of the tongue enters the slot 35 in the rear wall of the envelope, and is 30 secured in the manner previously described. Tongues 33 and 34 extend laterally from the tongue 31 and are provided with slots 33' and 34', the tongues being adapted to enter slots 36 in the rear wall.

35 In that form of the device shown in Figures 6 and 7 the stamp 38 is provided with four tongues 39 for cooperation with the four slots 40 located as shown. Two of these slots are in the usual flap of the envelope, 40 and the other two are in the rear wall thereof. The tongues are sealed on both sides in the manner previously described.

A further form of the device, which is especially useful and desirable, because of its 45 simplicity and efficiency, is shown in Figure 8. The usual closing flap of the envelope is provided with a tongue 42 having a coating of adhesive material on both sides there-

of and having a slot 43 therein. The stamp is located as shown, and the paper may be 50 folded along the line designated 44, to permit easy insertion of the tongue.

In Figure 9 I have shown a form in which the usual closing flap is provided with three 55 tongues 46, 47 and 48, each provided with a transverse slot, and having a coating of adhesive material on both sides. The stamp is located as shown, and the tongues are secured in the same manner as in the previously described form.

60 The perforations or slits 24, 25 shown in Figure 1 and elsewhere, will result in the tearing of the paper if the envelope is tampered with, making it apparent that an attempt has been made to open the envelope 65 before reaching the addressee.

Having thus described the invention, what I claim is:

1. An envelope having a slot through a 70 wall thereof, a sealing member for a closure flap of the envelope insertable through said slot and containing an application of adhesive for disposition within the envelope, said sealing member having a slot therethrough to remain exposed and unobstructed exteriorly of the envelope when the latter is closed to facilitate application of a moistening means therethrough to said adhesive.

2. An envelope having a first and a second wall, said first wall having a slot there- 80 through, a sealing member for a closure flap of the closure envelope insertable through said slot and containing an application of adhesive for disposition within the envelope facing the second wall, said sealing member 85 having a slot therethrough to remain exposed and unobstructed exteriorly of the envelope when the flap is closed to facilitate application of a moistening means therethrough to said adhesive.

90 In testimony whereof I affix my signature in presence of two witnesses.

MICHAEL H. FLAHERTY.
